FURNACE.

1,346,801.

Specification of Letters Patent. Patented July 13, 1920.

Application filed March 23, 1915. Serial No. 16,482.

To all whom it may concern:

Be it known that we, WILLIAM J. DOYLE and JUSTUS J. WOLLENHAUPT, citizens of the United States, and residing at Cincinnati, in the county of Hamilton and State of Ohio, have invented a new and useful Improvement in Furnaces, of which the following specification is a full disclosure.

The invention relates to an improvement in hot-air furnaces, and to a type in which the heater and independent cold and heater air passages are combined into a unitary structure, the air passages surrounding the heater and intercommunicating at a point below the heating zone of the heater. This produces a substantially pipeless furnace for heating all of the rooms of a building or apartment in which the heated air is delivered directly from the furnace through a register to a room immediately above the furnace and the cool air is returned through the same register to the furnace to be re-heated.

An object of the invention is to provide an insulated and heat non-radiating partition, comprising manifold spaced casings forming a jacket space interveningly between the hot and cold air passages, to minimize radiation so that the higher temperature in one passage will not materially change the temperature in the other and thereby increase the efficiency of the furnace.

Further objects and features of the invention will be more fully set forth in the description of the accompanying drawing, forming a part of this specification, and in such drawings like characters of reference denote corresponding parts throughout the several views, of which:—

Figure 1 is a central vertical section through the furnace with portions thereof shown in elevation.

Fig. 2 is a section on line 2—2, Fig. 1.

This invention, as an improvement in furnaces, contains the general features of advantage described and claimed in Letters Patent No. 1,133,242, to William J. Doyle and Justus J. Wollenhaupt, dated March 23rd, 1915, and characteristic to such type of furnace known to the trade as a pipeless furnace or system of heating, wherein the furnace serves as a means for withdrawing the cold air from the connected apartment,

conveying it to the heater to be heated and again delivered into the apartment, heating all the connected rooms, primarily to the elimination of conductor branches leading from the furnace independently to each room.

In the construction illustrated the furnace comprises a unitary structure of heater and hot and cold air passages, connecting through a register with a room immediately above the furnace. This type offers many advantages, being easily and cheaply installed, compact and simple, reducing cost of manufacture and shipping charges, and as a heater saving in the cost of fuel because heavy firing may be detrimental to a satisfactory operation in quickly establishing and maintaining a determined degree of temperature in the rooms to be heated. The heated air rises, forcing the colder air downward, and by the suction of the furnace is drawn into and downwardly through the cold air passage and then passes upwardly into and through the hot air passage around the heater, to be heated and delivered into the room. The air when heated expands, increasing its velocity which has a resulting effect on the velocity of the incoming cool air. When the furnace is started the circulation is relatively active, but gradually slows down, as the air entering the inlet approximates the temperature of the air emerging from the outlet, so that when the predetermined temperature has been attained and rendered substantially uniform throughout the house, the circulation is relatively passive and may be maintained by running the furnace at a relatively low heat. Thus the difference in degrees of temperature between the incoming and outgoing air determines the velocity of the air which is automatically accelerated when the variance in temperature is marked and is more sluggish when the temperature approaches degrees of uniformity.

It is, therefore, essential that the temperature of the incoming air is not materially changed by radiant heat from the heater or passage partitions, for if such cold air passage were unduly heated, it would interfere with the air circulated when both passages would become radiant heat conductors.

The heater in its construction comprises

the ash-pit 1, fire-box 2, combustion chamber casing 3 and hot-air radiator 4 of separable sections detachably united, following an established practice in the art. The radiator 5 4 has its axis disposed eccentrically to the axis of the combustion chamber casing and fire-box to centralize the radiator sections 10 relatively to the casings and bring the remaining sections of the heater into closer proximity with the face plate 5, to reduce the length of the passages 6 and 7 connecting the heater and face plate. The plate provides a support for the doors of said 15 passages and other furnace controlling parts. The heater is surrounded by a manifold number of casings spaced from each other and from the heater, including an outer casing 8 fixed to and supported upon the base plate 9 and to the face plate 5. 20 The casing is somewhat contracted at its upper portion with the upwardly and inwardly tapering portion 10 and terminates in a vertically extended portion 11 which connects with a register 12. A second casing 25 13 is concentrically supported within the outer casing 8 and spaced therefrom to provide a cold air passage 14. This second casing 13 is suitably supported to extend slightly below the heating zone and connect 30 said passage 14 with the hot-air chamber or passage 15 between heater and casing 13. The upper portion of said second casing 13 is similar in shape to that of the outer casing, having the upwardly and inwardly tapering cone portion 16, terminating with the 35 vertically extended portion 17 connected with the register 12. Concentrically within the inner casing 13, spaced therefrom and suitably supported, we provide a third casing 40 18 providing a jacket passage 19 open at the top and bottom. The intermediate passage 19 communicates at its upper end with the hot air passage to escape and maintain a circulation of air through said passage. The casing 18 and intermediate passage provide insulation for the casing 13. In the actual construction of furnace, the 45 degree or width of spacing between the casings 13 and 18 proportionately compared is considerably greater than the space between the casings 13 and 18 shown in the drawings. This in the drawings is merely for the purpose of more conveniently illustrating. Thus a portion of the cold air from 50 passage 14 enters the intermediate passage 19, circulating upward as its temperature changes from the heat radiating from the casing 18, with the temperature controlling the velocity of the air. In such construction of furnace, the temperature of the incoming cold air is not materially changed in 55 the passage 14, and, therefore, the velocity

of the air is not retarded by the change of its temperature in passing through said passage. The inner casing 13 connects with the face plate from a wall around the feed and ash-pit snouts 6 and 7 respectively, providing a pocket or chamber communicating with the hot-air passage. 65

Having described our invention, we claim:—

1. The combination of a furnace body comprising an ash-pit, combustion chamber and radiator, having laterally extending ash and feed snouts and products of combustion conduit, respectively, three separated casings surrounding said heater body, a single superposed floor register with which the upper ends of said casings communicate, to constitute an outer, downward, cold-air intake and passage and an inner, upward hot-air passage and outlet, the outer casing extending to the furnace base to inclose the heater, the two inner casings providing at the bottom communication between the outer cold-air passage and the heating spaces between the two inner casings and between the inner casing and the heater body, a terminal plate for the ash and feed snouts connected to the outer casing, the two inner casings having cut-out portions constituting a feed snout pocket, the cold-air passage formed by the two outer casings, being separated from said pocket to throw the heat radiated from the feed snout into an ascending hot-air passage. 85

2. In a hot-air single register furnace, the combination with a heater having projecting ash-pit and combustion chamber passages, and three casings one within another in a spaced relation and surrounding the heater, constituting an outer casing extending from the base of the heater to a register in the floor above the heater, an intermediate casing extending from the register to a point slightly above the base of the heater to provide an inner upward hot-air passage around and above the heater, and with said outer casing providing an outer downward cold-air passage communicating at the base with the upward passage, and the third or inner casing forming a protector for the intermediate casing and therewith forms a narrow intermediate upward air passage or insulating space. 100

In witness whereof we hereunto subscribe our names as attested by the two subscribing witnesses.

WILLIAM J. DOYLE,
JUSTUS J. WOLLENHAUPT.
